WILLIAM H. NORTHALL, OF EVANSVILLE, INDIANA, ASSIGNOR OF ONE-HALF TO
FREDERICK W. GOEDEKE, OF EVANSVILLE, INDIANA.

SELF-CENTERING SLIDE FOR EXTENSION-TABLES.

1,228,233.

Specification of Letters Patent. Patented May 29, 1917.

Application filed May 2, 1914. Serial No. 835,956.

To all whom it may concern:

Be it known that I, WILLIAM H. NORTHALL, a citizen of the United States, residing at Evansville, in the county of Vanderburgh and State of Indiana, have invented a new and useful Self-Centering Slide for Extension-Tables, of which the following is a specification.

This invention has reference to improvements in self centering slides for extension tables, and its object is to provide a slide for the purpose at all times positive in action, and which will avoid certain objections to other slides of like character, the construction of the slide adapting it especially for manufacture in most part of pressed steel.

In accordance with the present invention each slide comprises two runners made fast to respective sections of the table, and these 20 runners are movable lengthwise along an intermediate section or member which may be made fast to a central pedestal where the slides are used upon such type of extension table. The runners are interconnected in a 25 manner causing them to move simultaneously to like extents in opposite directions, so that the table sections are always self centered, and the whole table is appropriately balanced. The invention also includes 30 a locking means carried by one of the runners and engaging the intermediate member, so that the table when locked cannot be further extended, but may be readily collapsed or moved to a less extended position.

The invention will be best understood 35 from a consideration of the following detailed description, taken in connection with the accompanying drawings forming a part of this specification, with the further understanding that while the drawings show a 40 practical form of the invention, the latter is not confined to any strict conformity with the showing of the drawings, but may be changed and modified so long as such 45 changes and modifications mark no material departure from the salient features of the invention.

In the drawings:—

Figure 1 is a bottom plan view of a table 50 top, showing the pedestal in cross section

and illustrating the application of the present invention to a pedestal extension table.

Fig. 2 is a fragmentary view similar to Fig. 1 showing the table top extended. 55

Fig. 3 is a top plan view of one of the slides with small portions of the crossed arms carried by the pedestal.

Fig. 4 is a side elevation of the structure of Fig. 3 with the crossed arms in cross section. 60

Fig. 5 is a longitudinal central section of the slide.

Fig. 6 is a section on the line 6—6 of Fig. 5, but drawn on a larger scale. 65

Fig. 7 is a section on the line 7—7 of Fig. 4 but drawn on a larger scale.

Fig. 8 is a perspective view of one end of the intermediate member of the slide.

Referring to the drawings, there is shown 70 in Figs. 1 and 2 a table top 1 composed of two members 2, 3, as is customary, and there is also shown a pedestal 4 provided with the usual crossed arms 5 designed to receive slides which in turn are connected to the 75 table top as is the practice in extension tables. In Fig. 1 the table is shown in the closed position, and in Fig. 2 in the extended position with intermediate leaves 6 in place.

It is customary to provide two slides each 80 carried by corresponding ends of the crossed arms, and as the slides are alike the following description will be limited to the construction of one slide, it being understood that the other slide is but a duplicate 85 thereof.

Each slide comprises an intermediate member 7 and side members 8, 9, respectively, these side members being usually of about the same length as the intermediate 90 member and constitute runners made fast to the respective table top sections 2 and 3 as will presently appear.

The intermediate member 7 is a channel member with sides joined by a connecting 95 or yoke member 8^a and at the ends remote from the connecting member provided with outstanding flanges 9^a, 10, respectively. Near each end the channel member is provided with inturned partially punched out 100

ears 11 each of a length so that one overlaps the other, and these ears are formed with matching perforations 12 for the passage of a bolt 13 extending through another 5 perforation 14 in the connecting member or wall 8^a, and since in the installed position the wall 8 is usually the uppermost portion of the connecting member it will for convenience of description be termed the upper 10 wall. Ears 11 and a bolt 13 are provided for each end of the channel member 7, and the bolt is carried through the corresponding end of a cross arm 5 so that these crossed arms support the channel member 15 at the ends. To stiffen the parts and take the strain off the bolt the flanges 9^a and 10 are each provided with a punched out spur 15 which may be shaped to terminate in a relatively sharp point, so as to be driven 20 into the corresponding portion of the respective cross arm 5, thereby in conjunction with the bolt 13 anchoring the channel member in position against such displacement as would bring undue strain upon the 25 bolt. The ears 11 and the teeth or spurs 15 also serve as stiffening means for the sides of the channel member 7 at the ends thereof. At appropriate points the channel member is traversed by pins 16 carrying rollers 30 17 exterior to the side walls of the channel member, two of the rollers being located on one side of the channel member between the middle portion thereof and one end, and the other rollers being located on the other side 35 of the channel member between the middle portion and the other end. Each roller is of disk-like form with a dished central portion 18 serving to space the body of the roller away from the side of the channel 40 member to an extent corresponding to the depth of the dished part or hub of the roller. These rollers are of a diameter to extend for an appropriate distance above the top 2 of the channel member when the 45 latter is properly installed.

Mounted on the rollers 17 on opposite sides of the channel member are the runners 8 and 9, respectively, these runners being each made of sheet metal with the opposite long edges returned upon themselves as shown at 19 and 20, respectively, and spaced away from the body of the respective runner to form edge channels for the peripheries of the rollers 17 so that these 50 runners may move longitudinally upon the rollers and at the same time be held into close relation to the channel member by such rollers where they enter the guiding channels formed by the flanges 19 and 20. Each 55 runner is formed with a longitudinal central bead 21 offstanding from the face of the runner remote from the channel member, this bead serving in the main to stiffen the runner and also to support certain

mechanism, to be described, carried by one 65 of the runners. Struck out from each runner near the return edge 19 are tongues 22 each provided with an appropriate perforation 23. These tongues are located wholly to one side of the middle portion of the respective runner, one runner having the tongues at the opposite end to those of the other runner. Each runner also carries at a point close to its middle portion, but on the same side thereof as the tongues 22, a 75 bracket 24 provided with a perforation 25, the bracket 24 with its perforation 25 serving the same purpose as the tongues 22 and their perforations 23. It is by means of these tongues that the runners are made fast 80 to respective sections 2 and 3 of the table top, it being customary to employ screws 26 for the purpose.

That side of the channel member 7 adjacent to the runner 8 has an elongated recess 27 formed in its lower edge and the in-turned edge 20 of the runner 8 carries a bracket 28 extending through the recess 27 into the interior of the channel member 7.

The edge 19 of the runner 9 carries a 90 bracket 29 similar to the bracket 28 and extending toward the other runner 8 in overriding relation to the top 8 of the channel member 7. Mounted within the channel member upon supporting journal pins 30 95 are flanged rollers 31, there being two such rollers nearer to the corresponding ends of the channel member than are the ends of the slot 27, and these rollers are so related to the channel member as to in part extend 100 through slots 32 in the top 8^a of the channel member.

The brackets 28 and 29 have respective pins 33, 34 thereon and to these pins an endless chain 35 is secured. This chain may not be actually endless, but is effectively endless for it may be made up of a single section, or more than one section fastened to both pins 33 and 34. One run of the chain extends from the pin 33 through the lower portion of the channel member 7, around and over the roller 31 at the end of the slide remote from that near which the bracket 28 is normally located, and from thence the chain extends and is secured to the pin 34. The same chain or another chain extends from the pin 34 over the top 8^a of the channel member, which top may be slightly dished to receive and guide the chain, until the chain reaches the other roller 31 and is carried around and under this roller to the pin 33 of the bracket 28. The chain is thus effectively endless, and if either slide be moved lengthwise the other slide is constrained to also move lengthwise, but in the opposite direction due to the presence of the direction-changing rollers 31, and the movement is permitted by 110 115 120 125

reason of the supporting rollers 17 which are spaced far enough apart to effectively support the runners without permitting them to tip to any noticeable extent. The 5 chain 35 may also be taken as indicative of any flexible strand other than a chain which will permit like operations.

The flange 10 has up-struck teeth 36 arranged in groups along its length at spaced 10 intervals, and these teeth are in the path of the nose end 37 of a latch dog 38 mounted on a pivot pin 39 carried by the runner 9, although the same arrangement might be provided for the runner 8 instead of the 15 runner 9. It is, however, needful to have but one of the runners of the slide provided with latch means. The latch dog 38 is provided with an angle arm 40 on the side of the pivot 39 remote from the nose 37, and this arm 40 is extended through slots 41 formed in the bead 21 of the corresponding 20 runner. The latch 38 is located near one end of the runner constituting the forward end of the runner in the closing movement, 25 and the rear or trailing end of the runner in the opening movement. Near the other end of the runner there is mounted a manipulating lever 42 secured to the runner by a pivot pin 43, and this lever has one of 30 its arms extending through slots 44 in the bead 21. The arm of the lever 42 extending through the slots 44 and the arm 40 of the latch dog are connected together by a reach rod 45 so that upon a suitable manipulation 35 of the lever 42 the latch dog is moved in a direction to carry the nose 37 out of the path of the teeth 36. The latch devices are however constrained to the locked position by a spring 46 engaging the latch dog and 40 mounted on the pin 39 with the other end of the spring locked against the bead 21 or otherwise secured.

If it be assumed that the table top is in the closed position as indicated in Fig. 1 45 then any attempt to draw the two parts of the table top apart is resisted by the latch dog 38 with its nose in engagement with one of the teeth 36. In order to draw the sections of the table top apart it is necessary to first manipulate the lever 42 to thereby lift the nose 37 of the dog 38 out of the path of the teeth 36, after which the table top sections may be readily pulled away one 50 from the other to any desired extent, and then the leaves 6 are inserted in appropriate 55 number. On moving the table top sections together until stopped by the leaves, no resistance is offered by the dog 38, since the section 9 as viewed in Fig. 4 is then moved 60 toward the left and the nose of the dog rides idly over the teeth 36 until the engagement of the table top sections with the leaves prevents further movement and the dog locks against a tooth 36 then in its path,

so that the table is held firmly in the desired 65 position. By arranging the teeth 36 in groups at spaced points corresponding approximately to the width of the leaves 6, the same structure may be employed for different tables having leaves of some difference in width without the necessity of 70 changing the tools employed in the manufacture of the slide.

The connecting means between the runners causing them to move simultaneously 75 to equal extents is in most part housed within the central channel member and one run of the chain travels along the upper surface of the top of the channel member, thus permitting a relatively narrow slide 80 with the runners practically solid from end to end, and consequently correspondingly strong, while the sides of the channel member are not weakened by any material cutting away thereof. This is due to the arrangement of the chain, so that its runs are in substantially one upright plane, considering the structure as installed, while the whole structure is very much compacted, 85 and its strength is in no manner minimized 90 by cutting away parts which contribute materially to the rigidity of the runners and their supports.

In another application for self-centering 95 slides for extension tables filed by me on even date herewith there is disclosed a table slide having features in common with the table slide herein disclosed, and in the said other application claims are made to features common to both disclosures, wherefore 100 no claim is herein made to the broader features of the invention.

What is claimed is:—

1. A table slide comprising an intermediate member and flanking members on opposite sides thereof extending above the intermediate member, supports for the flanking members on the sides of the intermediate member and along which supports the flanking members are movable lengthwise, and a chain and direction-changing rollers therefor carried by the intermediate member and connected to the flanking members, said chain and rollers being located on the intermediate member between the sides and rising above the top thereof.

2. A table slide comprising a central or intermediate metallic channel member, flanking metallic runners having longitudinal channels at opposite edges, supporting rollers carried by the channel member exterior thereto and engaging the edge channels of the runners, rollers mounted within the channel member near opposite ends thereof and in part projecting through the top portion of the channel member, and an effectively endless chain connected to the respective runners near opposite ends there-

of, one run of the chain extending through the channel member and the other run extending over the channel member.

3. A table slide comprising an elongated 5 channel member with edge flanges each having spurs or teeth near the ends and said channel member having inturned overlapping ears adjacent to the spurs, with the ears and a corresponding portion of the 10 channel member provided with matching perforations for the passage of a fastening bolt, and runners mounted on and movable along the channel member.

4. A table slide comprising an elongated 15 channel member with means at the ends for attachment to a relatively stationary portion of a table, longitudinally movable runners mounted on and carried by the channel member exterior thereto and having means for 20 attachment to the sections of a divided table top, and means for causing the simultaneous movement of the runners in opposite directions comprising rollers mounted in the channel member and in part extending 25 through the top thereof, and an effectively endless chain extending about the rollers with one run above the channel member and the other run within the channel member, and with said runs connected to respective 30 runners.

5. A table slide comprising an elongated channel member with means at the ends for attachment to a relatively stationary portion of a table, longitudinally movable runners 35 mounted on and carried by the channel member exterior thereto and having means for attachment to the sections of a divided table top, and means for causing the simultaneous movement of the runners in opposite directions comprising rollers mounted in the channel member and in part extending 40 through the top thereof, and an effectively endless chain extending about the rollers with one run above the channel member and the other run within the channel member, one runner having a bracket above the channel member and the other runner having a bracket extending into the channel member 45 near the lower portion thereof and both 50 brackets being connected to respective runs of the chain.

6. A table slide comprising an elongated channel member with outstanding supporting flanges, one being formed with series of 55 teeth, elongated runners carried by the slide on opposite sides thereof and each provided with a longitudinal stiffening bead, interconnecting means between the runners for causing their simultaneous movement in opposite directions, and a latch means comprising 60 a latch dog mounted on one of the runners in position to engage the teeth on the corresponding flange of the channel member, a manipulating lever mounted on the

same runner with the bead of the runner 65 slotted for the passage of a portion of the lever and a portion of the latch dog, and a reach rod between the lever and dog.

7. A table slide, comprising an intermediate member, means for retaining said intermediate member in fixed relation to the table, rollers on opposite sides of and near respectively opposite ends of the intermediate member, runners attached to movable parts of the table and located on opposite 75 sides of the intermediate member close thereto and rising higher than the intermediate member to thereby define a channel above the intermediate member between the runners, guides on the runners engaging the 80 rollers to travel thereon and thereby interlock the runners with the intermediate member, and means for causing the simultaneous movement of the runners in opposite 85 directions, comprising a chain connected to respectively opposite end portions of the two runners, and guide rollers for the chain journaled to the intermediate member, said chain traveling along the channel between the runners above and supported on the intermediate member, whereby sagging of the 90 chain where so traveling is prevented.

8. A table slide comprising an intermediate member, means for retaining said member in fixed relation to the table, rollers on 95 opposite sides near respectively opposite ends of the intermediate member, flanking runners on opposite sides of and rising above the top of the intermediate member and mounted on and carried solely by the rollers 100 and retained by the latter on the intermediate member, and means for causing the simultaneous movement of the runners in opposite directions lengthwise of the runners and intermediate member, comprising an effectively endless chain connected to the respective runners near respectively opposite ends thereof, and direction changing rollers 105 for the chain mounted on the intermediate member, both the chain and last-named 110 rollers rising above the intermediate member and located between the sides of the intermediate member in the space below the tops of the runners and said chain where moving between the runners above the intermediate member being supported by the latter.

9. In a table slide, the combination of an intermediate member, rollers secured to the opposite sides of the intermediate member 115 near opposite ends to each rotate upon a horizontal axis, runners arranged on opposite sides of the intermediate member and mounted on and carried solely by the rollers 120 for movement along the intermediate member, said runners rising above the intermediate member close thereto and defining therewith a channel above the intermediate 125

member between the runners, an effectively endless chain connected to the respective runners and located to travel in the channel between the runners and on top of the intermediate member to prevent sagging of the chain where so traveling, and direction-changing rollers for the chain mounted on the intermediate member.

In testimony that I claim the foregoing as my own, I have hereto affixed my signature in the presence of witnesses.

WILLIAM H. NORTHALL.
